UNITED STATES PATENT OFFICE.

ANDRÉS PONCE DE LEON, OF MANILA, PHILIPPINE ISLANDS.

AUTOMATIC ERASER.

1,363,848.

Specification of Letters Patent. Patented Dec. 28, 1920.

Application filed February 19, 1920. Serial No. 359,904.

To all whom it may concern:

Be it known that I, ANDRÉS PONCE DE LEON, a citizen of the United States, residing at Sampaloc, Manila, Philippine Islands, have invented certain new and useful Improvements in Automatic Erasers; and I do hereby declare the following to be full, clear, and exact description of the invention, such as will enable others skilled in the art to 10 which it appertains to make and use the same.

This invention relates to new and useful improvements in erasing devices and particularly to devices for erasing printed matter such as typewriting, or other writing or printing.

One object is to provide a novel and improved device of this character which is automatic in its operation, thus relieving the 20 operator of the physical exertion of manipulating the eraser.

Another object is to provide a novel and improved device of this character which includes a motor for rotating the erasing element, with novel means for starting and stopping said element.

A further object is to provide a novel and improved device of this character wherein the speed of rotation of the erasing element 30 can be easily and positively governed.

Other objects and advantages will be apparent from the following description when taken in connection with the accompanying drawing.

35 In the drawing:

Figure 1 is a front elevation of my improved eraser.

Fig. 2 is a side elevation of the same.

Fig. 3 is a vertical central sectional view 40 taken on the line 3—3 of Fig. 1.

Fig. 4 is a vertical sectional view taken on the line 4—4 of Fig. 3, just inside of the front wall of the casing.

Fig. 5 is a vertical sectional view taken 45 on the line 5—5 of Fig. 3, just inside of the rear wall of the casing to show the escapement.

Referring particularly to the accompanying drawing, 10 represents a casing having 50 the removable back wall 11 and the lower offset extension 12, formed thereon. The front wall of the casing, in the lower portion is formed with a curved opening which is slightly greater than a half circle, as 55 shown at 13, and surrounding this opening is the externally threaded flange 14 for en-

gagement of the segmental and internally threaded disk 15. Through the center of this disk there is formed an opening 16 and through the offset extension 12 there is 60 formed a similar opening in alignment therewith. These openings receive the opposite ends of the shaft 17. In the inner face of the center of the front wall of the casing there is formed a boss 18 having a central 65 socket 19 for the reception of the adjacent end of the main spring shaft 20. The other end of this shaft is rotatably supported in an opening 21 in the center of the bottom wall of the hollow boss 22 formed in the center of the rear removable wall of the casing. Formed on the outer face of this latter boss is a circular flange within which the angular portion 23 of the shaft is exposed and arranged for the engagement 70 thereon of a key 24 for winding the spring 25 which is disposed within the casing or drum 26 through which the shaft 20 is centrally disposed. One end of the spring 25 is secured to the shaft 20 while the other 80 end is secured to the drum. On the shaft 20, within the hollow boss there is secured the ratchet wheel 27 which is engaged by the escapement pawl 28 pivoted on the bottom wall of the said boss. Forming the 85 front wall of the drum, and secured for rotation therewith, is a large pinion 29 which meshes with smaller pinion 30 mounted on a shaft 31 which is supported by the front wall of the casing in the upper portion of 90 the opening 13. Also mounted on the shaft 31 is a somewhat larger pinion 32, and this pinion meshes with a smaller pinion 33 on the shaft 17.

Secured on the shaft 17 is a sleeve 34 95 which is formed with a flange 35, and engaged on the sleeve and clamped against the flange by means of the disk 36, which is screwed onto the outer end of the sleeve, is a disk eraser element 37, the lower portion 100 of which projects from the bottom of the casing, while the upper portion turns within the plate or disk 15.

The periphery of the drum is formed with a series of openings 38, as clearly shown in 105 the drawing. Pivottally mounted on the inner face of one of the side walls of the casing is an angle lever 39 one end being formed with a nose 40 for engagement in any one of the openings 38 of the drum. A spring 41 presses the lever so as to urge the nose 110 into the openings, while a button 42 is car-

ried by the other end of the lever and extends through an opening 43 in the side wall of the casing for engagement by the finger or thumb of the operator. On the inner 5 face of the button carrying end of the lever there is secured a leather or rubber button 44 which is arranged for engagement with the peripheral face of the drum when the outer button is pushed inwardly beyond the 10 position where the lever's nose is disengaged from an opening of the drum. This permits the operator to control the speed of the rotation of the drum, when the motor is started, so that the erasing disk will not turn 15 too fast. The spring 41 is designed to instantly swing the lever into such position that its nose will be reengaged in one or another of the openings 38, when the outer button 42 is released.

20 In the operation of the device, the operator simply places his finger on the button 42 and presses inwardly, with the result that the nose of the lever will be released from the drum and the drum permitted to drive 25 the erasing element through the medium of the pinions. The operator then presses the erasing disk against the paper at the point the erasure is to be made and holds the device in such position until the marks have 30 been removed. Should the disk revolve too rapidly the operator simply presses the button inwardly a little farther when the rubber or leather button will engage frictionally with the drum and retard its rotation. The

instant that the button 42 is released the 35 lever reengages the drum and stops motion.

What is claimed is:

1. An automatic eraser comprising a casing, a motor in the casing including a rotatable drum, an erasing element driven by the 40 motor, a manually releasable detent for holding the motor inactive, said detent being movable through a part of its movement to release the motor, and means carried by the 45 detent and engageable with the drum upon movement of the detent past its releasing movement to act as a brake on the drum.

2. An automatic eraser comprising a casing, a motor in the casing including a rotatable drum having a longitudinal series of 50 openings in its periphery, an erasing element driven by the motor, and a manually releasable detent including a centrally pivoted lever mounted in the casing and having an angularly extending nose on one end for 55 releasable and interchangeable engagement in the openings of the drum, a fingerpiece on the other end of the lever movable through one wall of the casing, and a friction member carried by the inner face of the last-named end of the lever for engagement with the peripheral face of the drum.

In testimony whereof, I affix my signature in the presence of two witnesses.

ANDRÉS PONCE DE LEON.
